RONALD BRINKERHOFF SMITH, OF EAST ORANGE, NEW JERSEY.

VALVE-GEAR.

1,169,690.

Specification of Letters Patent. Patented Jan. 25, 1916.

Application filed June 18, 1915. Serial No. 34,849.

To all whom it may concern:

Be it known that I, RONALD B. SMITH, a citizen of the United States, and a resident of East Orange, in the county of Essex and State of New Jersey, have invented a new and Improved Valve-Gear, of which the following is a full, clear, and exact description.

This invention relates to valve gears and has for an object the provision of an improved arrangement whereby a valve may be opened to the usual extent and held open an appreciable time.

Another object of the invention is to produce a valve gear or mechanism for multiplying the movement of the valve shaft whereby a cam occupying a predetermined number of degrees of a circle may open and close the valve and also provide a period when the valve is held stationary in its maximum open position.

A still further object of the invention is to provide a valve gear in which an easy acting cam is utilized and a multiplying mechanism is provided so that the degree of movement caused by the cam may be reduced to a minimum while producing an opening of the valve *per se* equaling the usual opening.

In carrying out the objects of the invention the same may be applied to gas engines, puppet valves or to valves in any desired place and for any desired purpose. In puppet valves, for instance, the valve *per se* is usually opened to a maximum and then closed, the movement being continuous.

The present invention contemplates the utilization of means whereby the opening of the valve may be attained quickly and the closing of the valve may be attained quickly, while the maximum opening may be maintained for an appreciable length of time, thus producing a longer maximum opening than is produced by a gradual opening and a gradual closing valve. These results are produced by an arrangement of multiplying mechanism and a peculiarly formed cam which will produce the proper movement to the multiplying mechanism, which in turn multiplies such movement and acts in timed relation thereto for producing the proper action of the valve member *per se*.

In the accompanying drawings: Figure 1 is a detail fragmentary longitudinal vertical section through a valve and gearing embodying the invention. Fig. 2 is a sectional

view through Fig. 1 on line 2—2. Fig. 3 is a sectional view similar to Fig. 2 but disclosing a slight modified form of the invention.

60

Referring to the accompanying drawings by numerals, 1 indicates the manifold or discharge outlet for the exhaust of an explosive engine and 2 the valve *per se* which coacts with the seat 3 for opening and closing the manifold 1. Part of an explosive engine is shown in the drawing and the description will be in connection therewith, but it is to be understood that the invention may be applied not only to explosive engines 65 but to engines or machines of any construction to which the device may be adapted.

The valve member 2 is provided with a valve stem or rod 4 which projects through a suitable opening in the casing 5 and extends downwardly into a framework in the form of a casing 6. A stop 7 is formed integral with rod 4 or rigidly secured thereto in any desired manner so as to present an abutment for the spring 8 which also bears 70 against the casing 5 and is of such a length as to continually give the rod 4 and valve 2 a tendency to move downwardly, whereby the valve 2 may rest on its seat 3 when not positively moved therefrom. The part of 75 shaft 4 below abutment 7 extends through a suitable opening in the top or cap 9 of casing 6, and is provided with bearing members 10 and 11 fitting in guideways 12 and 13, as more clearly shown in Fig. 2, which 80 guideways may be mounted in the casing 6 in any desired way, as for instance, by screws 14.

On one side of the lower part of the rod 4 adjacent the bearing members 10 and 11 85 is arranged a rack 15, while on the opposite side is arranged a rack 16, these racks meshing with the gear wheels 17 and 18, respectively. The gear wheels 17 and 18 are journaled in arms 19 and 20 of a yoke 21, which 90 yoke is rigidly secured to a reciprocating bar 22 carrying a roller 23. The bar 22 is guided in its movement by a comparatively long bearing 24 extending from the casing 6. In connection with the wheels 17 and 18 95 100 it will be observed that the same, in addition to meshing with racks 15 and 16, also mesh with stationary racks 25 and 26 secured in any desired way to the casing 6, as for instance, by screws 27. The casing is 105 mounted in any suitable manner, as for instance by screws or bolts, to any desired part 110

of the engine or other stationary support. In providing the gear wheels 17 and 18, wheels of equal radius are preferably used.

As shown in Fig. 1, the roller 23 is adapted to continually engage the cam 28 which is rigidly secured to shaft 29, which continually rotates while the engine or other machine is in operation. If the device is connected with an explosive engine, shaft 29 is 10 geared or otherwise connected with the power shaft of the engine so as to operate in timed relation to the movement of the pistons in order to cause the opening and closing of valve 2 at the proper time. Cam 15 28 is provided with inclined cam faces 30 and 31 and a bearing face 32. The movement of the wheel 23 in opening valve 2 commences at approximately the point 33 and ends at point 34. The wheel then 20 engages the bearing face 32 until the point 35 is reached, whereupon the valve will begin to close and continue the closing movement until the wheel 23 reaches point 36, whereupon the valve is closed and will remain 25 closed during the further rotation of the cam until the point 33 is reached.

It is evident that the raised portion 37 on which the cam faces 30, 31 and 32 are arranged may be of any size and may occupy 30 any desired part of a circle. However, as an example, the drawing shows the same as occupying approximately 100° , the cam faces 30 and 31 occupying 30° each and the bearing face 32 occupying approximately 40° . By this construction and arrangement it is evident that the valve 2 will be opened from a closed position to a maximum open position during the 30° movement of cam 28 and will remain open at its 40 maximum for a 40° movement of the cam, and will then gradually close during a continued 30° movement. The raising movement of the lug 37 is, however, only half of the raising movement of the valve 2 by reason of the gear wheels 17 and 18 and the racks heretofore described which coact therewith. It is evident that multiplying 45 gears could be provided for causing an opening of valve 2 on a less movement of rod 22 and associated parts, if desired, without departing from the spirit of the invention, although ordinarily the multiplying of twice the movement is sufficient for ordinary use. The casing 6 entirely incloses the gear 50 wheels 17 and 18 and associated parts so, if desired, the same could be caused to operate in oil, or oil cups or oil mechanism of any kind could be supplied without in any way affecting the principle involved and without 55 departing from the invention.

In Fig. 3 is shown a slightly modified form of the invention in which gear wheels 38, 39 and 40 are provided on the arms of a yoke similar to the yoke 21 and are caused to 60 mesh with a plurality of racks 41 secured to

a housing 6'. Shaft 4 in this form of the invention is provided with an extension 4' having three sides, each side being provided with a rack for meshing with these respective gear wheels. This form of the invention clearly brings out the idea that the invention may be applied in a number of ways, as for instance, by a single gear wheel, a pair of gear wheels as shown in Fig. 1, three gear wheels as shown in Fig. 2, or other 70 numbers as may be desired. Where the work is light a single gear wheel would be desirable, but for a variety of cases, as for instance an ordinary explosive engine, the arrangement shown in Fig. 1 would be preferable, while a greater number of gear wheels would be desirable in case large valves were to be operated against a comparatively higher pressure.

It is of course evident that the racks and 75 gear wheels may be made from any desired material, but preferably the same are made from some durable alloy or steel so as to resist the wear during constant use.

What I claim is:—

1. In a valve gear of the character described, the combination with a puppet valve and a cam for operating the same, of a multiplying mechanism interposed between the cam and the valve for multiplying 95 the movement caused by the cam.

2. In a valve gear of the character described, a multiplying mechanism, a valve connected with said mechanism and adapted to be actuated thereby, an operating rod connected with said mechanism for actuating the mechanism, and a cam for actuating said rod, said cam being formed with a pair of inclined faces and a bearing face joining the outer part of said inclined faces, said bearing face being constructed on the arc of a circle with the center coincident with the center of the cam.

3. A valve gear comprising a valve operating rod for opening and closing the valve, 110 a rack connected with said rod, a gear meshing with said rack, a stationary rack meshing with said gear, a power rod for actuating said gear, and a cam for actuating said power rod.

4. In a valve gear of the character described, a valve adapted to be opened and closed, a rod extending from said valve provided with a plurality of racks, a gear wheel meshing with each of said racks, a 120 stationary rack meshing with each of the gear wheels, a power rod connected with said gear wheels for actuating the same, a cam for actuating said rod in one direction, and means for moving said rod in the opposite 125 direction.

5. In a valve gear of the character described, the combination with a valve member, of a plurality of racks connected therewith, resilient means for resiliently retain- 130

ing said valve closed and for moving the same to a closed position when moved therefrom, a gear wheel meshing with each of said racks, a stationary rack member meshing with each of said gear wheels, an operating rod connected with all of said gear wheels, and a cam for moving said operating rod in one direction.

6. In a valve gear of the character described, the combination with a valve, of a power member, means for multiplying the movements of said power member, said means actuating said valve in one direction, a spring for returning said valve, and a cam for actuating said power means, said cam being formed with a raised portion having a pair of oppositely inclined cam faces and a connecting bearing face whereby said power member is raised and then maintained in a raised position a predetermined length of time.

7. A valve gear comprising a multiplying mechanism connected with a valve member for moving the valve member, a power member for actuating said multiplying mechanism, and a cam for actuating said power member in one direction, said cam being formed with an annular portion merging into a raised portion, said raised portion being provided with a pair of cam faces and a connecting bearing face, said connecting bearing face being struck on an arc of a circle and parallel with the annular portion of the cam, whereby said power member is held stationary in its raised position while engaging said bearing face, the movement of the power member over said cam faces being a predetermined portion less than the movement of the valve according to the degree of multiplication of said power multiplying mechanism.

8. A valve gear comprising a rod adapted to be connected with the valve, a spring acting on said rod for normally holding the same in a given position, said rod being provided with a pair of racks and a pair of bearing members, a guide for each of said bearing members, a gear wheel meshing

with each of said racks, a stationary rack for each of said gear wheels meshing therewith, a yoke for supporting both of said gear wheels, a power member connected with said yoke for actuating the yoke in one direction, and a cam for actuating said power member, said cam moving said power member one half the distance that the valve connected with said rod is moved.

9. A valve gear comprising a rod adapted to be connected with a valve member, a spring for normally holding said rod in a given position, a plurality of racks arranged on said rod, a plurality of guides arranged on said rod, guideways for engaging said guides, a gear wheel connected with each of said racks, a stationary rack meshing with each of said gear wheels opposite said first mentioned racks, a member for connecting all of said gear wheels, a power member connected with said gear wheel connecting member, and a cam for actuating said power member and said rod against the action of said spring, said cam being provided with a pair of inclined faces and a connecting bearing face whereby said power member and parts associated therewith are raised and maintained in a raised position for a predetermined time and then lowered to their original position, thus producing a quick opening and closing of said valve and the maintenance of said valve in a maximum open position for a maximum time.

10. A valve gear comprising a valve operating rod for opening and closing the valve, a rack connected with said rod, a gear meshing with said rack, a stationary rack meshing with said gear, a power rod for actuating said gear, and an actuating power member for moving said power rod.

In testimony whereof I have signed my name to this specification in the presence of two subscribing witnesses.
